US00D762164S

(12) **United States Design Patent** (10) **Patent No.:** **US D762,164 S**
Lin et al. (45) **Date of Patent:** **** Jul. 26, 2016**

(54) **PORTABLE POWER SOURCE**

(71) Applicant: **GADMEI ELECTRONICS TECHNOLOGY CO., LTD.**, Qingyuan, Guangdong (CN)

(72) Inventors: **Hui Lin**, Guangdong (CN); **Zhihua Zhang**, Guangdong (CN)

(73) Assignee: **GADMEI ELECTRONICS TECHNOLOGY CO., LTD.**, Qingyuan (CN)

(**) Term: **14 Years**

(21) Appl. No.: **29/465,541**

(22) Filed: **Aug. 29, 2013**

(30) **Foreign Application Priority Data**

Jul. 24, 2013 (CN) 2013 3 0349683
Jul. 24, 2013 (CN) 2013 3 0349714

(57) **CLAIM**

The ornamental design for a portable power source, as shown and described.

DESCRIPTION

FIG. 1 is a front elevation view of a portable power source showing our new design;

FIG. 2 is a rear elevation view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.
